UNITED STATES PATENT OFFICE.

FREDERICK W. LEWIS, OF PROVIDENCE, RHODE ISLAND, ASSIGNOR TO CHAPIN & HOLLISTER CO., OF PROVIDENCE, RHODE ISLAND, A CORPORATION OF RHODE ISLAND.

BELT-BUCKLE.

1,350,076.

Specification of Letters Patent. Patented Aug. 17, 1920.

Application filed January 14, 1920. Serial No. 351,330.

To all whom it may concern:

Be it known that I, FREDERICK W. LEWIS, a citizen of the United States, and resident of the city of Providence, in the county of 5 Providence and State of Rhode Island, have invented certain new and useful Improvements in Belt-Buckles, of which the following is a specification.

This invention relates to buckles of the 10 class more particularly adapted to automatically grip and bind a belt in adjusted position about the body of the wearer; and the object of this invention is to provide a simple and practical buckle of this character 15 having a cross-bar working in inclined slots for positively engaging the belt, to prevent it from slipping in the buckle.

With these and other objects in view, the invention consists of certain novel features 20 of construction, as will be more fully described, and particularly pointed out in the appended claims.

In the accompanying drawings:

Figure 1— is a front view illustrating 25 my improved buckle as applied to a belt.

Fig. 2— is a sectional side elevation illustrating the cam action of my improved biting-roll-bar; also illustrating the arrangement of the slots in the side walls of 30 the buckle whereby their degree of inclination is gradually reduced relative to the plane of the face-plate as they approach this plate.

Fig. 3— is an enlarged detailed side elevation of the offset or cam-shaped biting-roll member.

Fig. 4— is an end view of this roll.

Fig. 5— is a section through the body of 40 the buckle on line 5—5 of Fig. 1, illustrating the biting roll in the slots.

Fig. 6— is a perspective view showing the under side of the buckle.

Fig. 7— is an enlarged end view of one 45 form of belt-gripping bar, showing the same as having oppositely-disposed cam portions.

It is found in practice that the ordinary cross-bar mounted in the usual inclined slots of a belt buckle, fails to hold the belt positively against slipping when unusual strain 50 is applied thereto.

To obviate this serious difficulty I have provided means in my improved buckle, which serve to increase the gripping and binding action of this bar so that it will

positively hold the belt in any adjusted position in the buckle. 55

To accomplish this in a simple and effective way, I have provided a buckle having the usual face-plate 10 with two rearwardly-extending side walls 11 at one end of which 60 is mounted the usual loop 12 to which a portion of the belt 13 is permanently secured. In order to obtain adjustment for the other portion 14 of this belt and to bite and retain this portion in adjusted position 65 I have provided a slot 15 in each of these side walls 11 which are arranged parallel with each other and which slots are set on an incline relative to the plane of the front plate. 70

It is well known that the less the inclination or angle of the slot where the clamping member enters the belt, the greater is the gripping and binding power of this clamping member. Therefore to produce this increased biting effect I have formed these slots 15 on somewhat of a circle whereby their outer ends have a relatively sharp inclination while their inner ends 16 are nearer parallel with the plane of the face plate 80 against which the clamping member bites the belt. 75

By this construction the biting roll or member which is mounted in these slots may be moved from its outer end quickly down 85 into engagement with the belt and after engagement therewith the biting action of said biting member will be more gradual, which lessened incline will correspondingly increase its biting or holding power. 90

I do not wish to be restricted to forming these slots on a circle as they may be made angular if desired, the object being that the inner portion of these slots shall have less inclination relative to the face-plate than the 95 other portion thereof.

The biting roll or bar 17 mounted in these slots is preferably provided with offset trunnion members 18 which are adapted to roll or slide in the slots 15 and the outer ends of these trunnion members are preferably reduced as at 19 onto which are riveted the retaining washers 20 to securely hold the biting roll member in position in these slots. 100

By offsetting these trunnion members the 105 biting roll or bar is provided with a cam action whereby when strain is applied to the belt a slight rotating motion of this roll

serves to cause its offset portion to more effectively grip and bind the belt against the inner surface of the front plate.

To insure rotation and action of this cam,

5 I preferably provide its surface with relatively-deep, longitudinal ribs or corrugations so as to cause it to positively engage and so prevent slipping of the roll on the belt.

10 By my improved construction of a cam-shaped biting bar and the gradual inclination of the slots, I have produced a buckle which will not slip and will positively hold the belt in any adjusted position.

15 In some instances instead of forming the cam bar with a single cam action, as illustrated in Fig. 4, I form the same with a double cam action, as illustrated in Fig. 7, which latter has a number of practical ad-

20 vantages over the single cam among others being first, the double-cam construction may be made cheaper by using the stock form of oblong wire and inserting trunnion 22 into the center hole thereof, and by which construction there is practically no stock wasted; and second, by the use of a double cam 23 and 24, the bar will bite on each 25 half of a revolution, while with the single cam if it does not begin to engage until it 30 has passed the center or major axis, it must make a complete revolution before the cam can act again.

The foregoing description is directed solely toward the construction illustrated,

but I desire it to be understood that I reserve 35 the privilege of resorting to all the mechanical changes to which the device is susceptible, the invention being defined and limited only by the terms of the appended claims.

40 I claim:

1. A belt buckle comprising a face-plate having rearwardly-turned side walls provided with inclined slots therein, and a cam-shaped belt-gripping bar rotatably mounted in said slots to bind the belt by a rotating 45 action against the inner surface of said face-plate.

2. A belt buckle comprising a face-plate having rearwardly-turned side walls provided with inclined slots therein, and a belt- 50 gripping bar rotatably mounted in said slots, said bar being provided with oppositely-disposed cam portions, each being adapted to grip and bind the belt by a rotating action against the inner surface of 55 said face-plate.

3. A belt buckle comprising a face-plate having rearwardly-turned side walls provided with oppositely-disposed inclined slots, a belt-biting member operatively mounted 60 to move in said slots, the entire length of said slots being formed on the arc of a circle and set so that their inner ends are at a less angle relative to the face-plate than their outer ends.

65 In testimony whereof I affix my signature.

FREDERICK W. LEWIS.
